UNITED STATES PATENT OFFICE

2,603,296

OIL WELL TREATING APPARATUS

Andrew Craig Russell, Shawnee, Okla.

Application June 20, 1949, Serial No. 100,280

2 Claims. (Cl. 166—17)

1

This invention relates to novel apparatus for use in connection with the treating of liquids by means of application of heat thereto, the primary object being to provide relatively simple, inexpensive and easily operated structure capable of automatically and thoroughly applying steam to oil and admixing the same whereby the oil is heated and thereby treated for any purpose desired.

In the petroleum industry, difficulty is quite often experienced in efficient operation of the wells themselves through coating of the walls thereof with paraffin and like substances that retard the free flow of the oils being pumped. Many attempts have been made to rectify the problem and it has been found that the most practical means is to apply heat thereto in order to melt the paraffin-like coatings, but the difficulty arises in a suitable means for heating such coatings.

It is the most important object of this invention therefore, to provide improved apparatus capable of treating oil wells or treating of any fluids through application of steam pressure thereto and admixing such steam with the oil to the end that the latter is heated and the paraffin content thereof is liquefied.

Another important object of the present invention is to provide apparatus for treating oils or oil wells having a hollow tank provided with an inlet and an outlet opening, the oil to be treated being directed into the tank and steam being conveyed to the oil for admixture therewith as the latter enters the aforesaid tank.

Another important object of the present invention is to provide a tank for receiving simultaneously the oil to be treated and steam for treating the same, the oil and the steam being thoroughly admixed by creating a turbulence within the tank and by causing the same to dwell therewithin for a predetermined period of time prior to release either back to the original storage tank or into a well to be treated.

Other more minor objects will be made clear or become apparent as the following specification progresses, reference being had to the accompanying drawing, wherein:

Fig. 1 is a schematic elevational view partially in section showing an oil well treating apparatus embodying my present invention; and

Fig. 2 is an enlarged, vertical, cross-sectional view through the treating tank per se.

In Fig. 1 of the drawing, there is shown fragmentarily a storage tank for oil or other fluid designated by the numeral 10. This tank 10

5 has an outlet connection with a pump 12 through a pipe 14 that in turn has a manual control valve 16 interposed therein. The outlet end of the pump 12 is connected by means of a line 18 with the lowermost end of an upright, hollow tank 20.

An outlet opening is formed in the tank 20 adjacent the uppermost end thereof communicating with a conduit 22 that in turn is provided 10 with a thermostatic valve 24 having its thermo element 26 connecting directly with tank 20.

An oil well broadly designated by the numeral 28 is of conventional character in that the same is provided with an elongated, hollow casing 30 15 and the usual tubing 32 through which the petroleum produced by well 28, is pumped by conventional mechanism not shown.

Conduit 22 connects directly with the casing 30 by means of a pipe 34 having a control valve 20 36 therein.

T-joint 38 between conduit 22 and pipe 34, couples with storage tank 10 by means of a conduit 40 provided with a control valve 42.

Fig. 2 of the drawing shows clearly the construction of tank 20 and its internal component parts. The line 18 extends upwardly into the tank 20 through the bottom thereof and terminates a short distance above the bottom of tank 20. A plurality of brackets 44 affixed directly 30 to the line 18 within the tank 20, carries a substantially semi-spherical baffle member 46 that is spaced above the innermost end of line 18 in direct alignment therewith.

A steam supply line 48 adapted for connection 35 with a source of steam under pressure not shown, has a control valve 50 and extends into the vertical portion of line 18 in the manner shown in Fig. 2. The uppermost end of the steam line 48 terminates above the lowermost end of the tank 20 and below the uppermost end of the line 18. The diameter of line 48 is appreciably smaller than the diameter of the line 18 and the uppermost open end of steam line 48 is flared outwardly as at 52.

45 In operation, when it is desired to treat the pores of the well 28 to condition the coating of paraffin therein to a point where the same is sufficiently liquid to pass with the oil through the tubing 32, the oil or other liquid within the tank 50 10 is permitted to flow by force of gravity to pump 12 by way of pipe 14 through the simple expedient of opening valve 16. Operation of pump 12 forces such liquid under pressure through line 18 and into tank 20. Simultaneously, the valve 55 50 is opened to permit steam pressure to pass

into the tank 20 by way of line 48. It is notable that the steam passing through line 48 will impinge upon the oil or other liquid in line 18 below the uppermost end of the latter and become thoroughly admixed therewith because of the flared outlet end 52 of line 48. As the admixed steam and oil flow into tank 20 at the uppermost end of line 18, such admixture will strike the lowermost face of the baffle member 46 and a turbulence will take place capable of assuring that the steam thoroughly mixes with the oil and heats the same fully and completely. The contour of the baffle member 46 will not interfere with the free flow of steam and oil but will change the direction of flow thereof, thereby assuring that maximum heating of oil takes place with a relatively small amount of steam.

The admixed steam and oil are permitted to dwell within the tank 20 for a sufficient period of time to heat the oil to a predetermined temperature. This dwelling action is accomplished through the thermostatic valve 24, the same opening only when the temperature is at a sufficiently high degree. The heated admixture thereupon passes through conduit 22, and with valve 36 open and valve 42 closed, the same will pass directly into the casing 30 through pipe 34. The heated fluid drops by force of gravity downwardly through casing 30 for admixture with the oil at the bottom of well 28 and when the same comes into contact with the paraffin coated pores of well 28, such paraffin will be loosened and permitted to flow from well 28 outwardly by way of tubing 32. The heated liquid passing through tubing 32 will also loosen any paraffin coatings that may be therein.

It is seen that the entire operation of treating well 28, can take place at any time without shutdown of the pumping operation.

In the event that it is desired to treat oil for any purpose whatsoever by heating the same, the same system and apparatus can be used by merely closing valve 36 and opening valve 42. The heated liquid passing through conduit 22 will thereupon return to the storage tank 10 by way of conduit 40. The recirculation of the liquid being treated may continue until such time as the treating operation is complete and satisfactory.

It is clear from the foregoing that there has been provided a simple, inexpensive and easily operated means for treating oil or any liquid by means of heat, whether by a recirculation process from a storage tank, or an oil well itself during operation thereof.

Many changes might well be made over and above the single embodiment hereof and it is, therefore, understood that such changes and

modifications as fairly come within the scope of the appended claims, are contemplated hereby.

Having thus described the invention, what is claimed as new and desired to be secured by Letters Patent is:

1. Apparatus for treating oil wells comprising a storage container for well-treating oil; a hollow tank; a conduit connecting the tank at the bottom thereof with said container; a pump interposed in said conduit for directing oil under pressure from the container into the tank; a pipe extending into the conduit and terminating in an open end within the tank for directing steam into the oil as the same flows into the tank; an outlet line at the top of said tank adapted for connection with an oil well to be treated and having a branch joining with the container; and valve means in said line and said branch respectively for selectively discharging oil and steam admixture from the tank into the well or into the container.

2. Apparatus for treating oil wells comprising a storage container for well-treating oil; a hollow tank; a conduit connecting the tank at the bottom thereof with said container; a pump interposed in said conduit for directing oil under pressure from the container into the tank; a pipe extending into the conduit and terminating in an open end within the tank for directing steam into the oil as the same flows into the tank; an outlet line at the top of said tank adapted for connection with an oil well to be treated and having a branch joining with the container; valve means in said line and said branch respectively for selectively discharging oil and steam admixture from the tank into the well or into the container, the ends of said conduit and said steam pipe within the tank being near the bottom of the latter; and a horizontal baffle in overlying, spaced relationship to said ends for deflecting the steam and oil entering the tank whereby to create a turbulence of admixed oil and steam in the tank.

ANDREW CRAIG RUSSELL.
